(57) **CLAIM**

The ornamental design for a shoe, as shown and described.

DESCRIPTION

FIG. 1 is a shoe shown in perspective.

FIG. 2 is an outer side view of the shoe.

FIG. 3 is an inner side view of the shoe.

FIG. 4 is a front view of the shoe.

FIG. 5 is a rear view of the shoe.

FIG. 6 is a top view of the shoe; and,

FIG. 7 is a bottom view of the shoe.

The evenly spaced broken lines represent claimed stitching. All other broken lines in the drawings represent environmental subject matter that forms no part of the claim.
